Inventor
T.G. Williams

By his Attorney
Clinton R. Williams

UNITED STATES PATENT OFFICE.

THEOPHILUS G. WILLIAMS, OF MORRISTOWN, NEW JERSEY.

DESIGN FOR A LADIES' HAND BAG.

Application filed June 28, 1927. Serial No. 22,591. Term of patent 14 years.

To all whom it may concern:

Be it known that I, THEOPHILUS G. WILLIAMS, a citizen of the United States, residing at Morristown, in the county of Morris and State of New Jersey, have invented a new, original, and ornamental Design for Ladies' Hand Bags, of which the following is a specification, reference being had to the accompanying drawing, forming a part thereof, in which—

I claim:

The ornamental design for a ladies' hand bag, as shown.

THEOPHILUS G. WILLIAMS.
